(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front view thereof showing the state that a circular indicator, which is located at the front-lower part of the mobile phone and has been lit during operation, disappears when the mobile phone is turned off.

The broken lines shown in the figures that occur within the claimed design and define unshaded and uninterrupted regions (i.e. the broken lines that show buttons and inputs around the edges) represent inner boundaries of the claim. The broken line display shown on the front represents environment that occurs beneath the continuous front surface. The broken lines showing the rear of the mobile phone represent environment. The broken lines form no part of the claimed design.
